CLAIM

The ornamental design for an oven as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view of a first embodiment of an oven from above and left;

FIG. 2 is a front view thereof;

FIG. 3 is a rear view thereof;

FIG. 4 is a right view thereof;

FIG. 5 is a left view thereof;

FIG. 6 is a base view thereof;

FIG. 7 is a top view thereof;

FIG. 8 is a perspective view of a second embodiment of an oven from above and left;

FIG. 9 is a front view thereof;

FIG. 10 is a rear view thereof;

FIG. 11 is a right view thereof;

FIG. 12 is a left view thereof;

FIG. 13 is a base view thereof;

FIG. 14 is a top view thereof;

FIG. 15 is a front view thereof of a third embodiment of an oven;

FIG. 16 is a right view thereof;

FIG. 17 is a left view thereof;

FIG. 18 is a top view thereof;

FIG. 19 is a perspective view of the third embodiment of the oven from front and right with door closed;

FIG. 20 is a perspective view of the third embodiment of the oven from front and right with door open;

FIG. 21 is a perspective view of the third embodiment of the oven from front and left with door closed;

FIG. 22 is a base view thereof (in which the handle of the oven is not shown due to the camera angle);

FIG. 23 is a rear view thereof;

FIG. 24 is a perspective view of a fourth embodiment of an oven from front and left with door closed;

FIG. 25 is a front view of the fourth embodiment of the oven with door open;

FIG. 26 is a right view thereof;

FIG. 27 is a left view thereof;

FIG. 28 is a top view thereof;

FIG. 29 is a perspective view of the fourth embodiment of the oven from front and right with door closed;

FIG. 30 is a perspective view of the fourth embodiment of the oven from front and right with door open;

FIG. 31 is a base view thereof (in which the handle of the oven is not shown due to the camera angle);

FIG. 32 is a rear view thereof;

FIG. 33 is a front view of the fourth embodiment of the oven with door closed;

FIG. 34 is a perspective view of a fifth embodiment of an oven from front and left with door closed;

FIG. 35 is a front view of the fifth embodiment of the oven with door open;

FIG. 36 is a right view thereof;

FIG. 37 is a left view thereof;

FIG. 38 is a base view thereof (in which the handle of the oven is not shown due to the camera angle);

FIG. 39 is a top view thereof;

FIG. 40 is a perspective view of the fifth embodiment of the oven from front and right with door closed;

FIG. 41 is a perspective view of the fifth embodiment of the oven from front and right with door open;

FIG. 42 is a rear view thereof;

FIG. 43 is a front view of the fifth embodiment of the oven with door closed;

FIG. 44 is a perspective view of a sixth embodiment of an oven from front and left;

FIG. 45 is a front view thereof;

FIG. 46 is a right view thereof;

FIG. 47 is a left view thereof;

FIG. 48 is a top view thereof;

FIG. 49 is a base view thereof (in which the handle of the oven is not shown due to the camera angle);

FIG. 50 is a perspective view of the sixth embodiment of the oven from front and right;

FIG. 51 is a rear view thereof;

FIG. 52 is a perspective view of a seventh embodiment of an oven from front and left;

FIG. 53 is a rear view thereof;

FIG. 54 is a right view thereof;

FIG. 55 is a left view thereof;

FIG. 56 is a base view thereof (in which the handle of the oven is not shown due to the camera angle);

FIG. 57 is a top view thereof;

FIG. 58 is a perspective view of the seventh embodiment of the oven from front and right;

FIG. 59 is a front view thereof;

FIG. 60 is a perspective view of an eighth embodiment of an oven from front and left;

FIG. 61 is a front view thereof;

FIG. 62 is a rear view thereof;

FIG. 63 is a right view thereof;

FIG. 64 is a left view thereof;

FIG. 65 is a base view thereof (in which the handle of the oven is not shown due to the camera angle);

FIG. 66 is a top view thereof; and,

FIG. 67 is a perspective view of the eighth embodiment of the oven from front and right.

The broken lines form no part of the claimed design.

The broken lines and the masked areas within them form no part of the claimed design.
